UNITED STATES PATENT OFFICE.

JAMES M. McCLELLON, OF EVERETT, MASSACHUSETTS.

SUPERHEATER.

No. 880,562.

Specification of Letters Patent.

Patented March 3, 1908.

Application filed January 30, 1905. Serial No. 243,356.

To all whom it may concern:

Be it known that I, JAMES M. McCLELLON, a citizen of the United States, residing at Everett, county of Middlesex, and State of Massachusetts, have invented an Improvement in Superheaters, of which the following description, in connection with the accompanying drawings, is a specification, like letters on the drawings representing like parts.

10 This invention relates to superheaters for steam, and has for its principal object to provide a novel superheater which is simple but effective in operation, and which is especially adapted to be used in locomotive boilers, although it may also be used in almost any type of boiler.

In accordance with my invention I form within the shell of the boiler a superheating chamber which is so constructed that both 20 hot products of combustion and the steam to be superheated can pass from one end to the other thereof, the hot products of combustion operating to superheat the steam during its passage through the superheating chamber. In applying my invention to a locomotive boiler, I place this chamber within the shell of the boiler and preferably extend it from the fire-box to the smoke-chamber. Within the shell are either flues 25 through which products of combustion pass from the fire-box to the smoke-chamber, or steam-pipes through which the steam passes. Where flues are used for conducting the products of combustion through the super- 30 heating chamber the arrangement is such that the space within the chamber around the flues is filled with steam, which steam becomes superheated by the heat radiating from the flues. Where the steam-pipes are 35 taken through the chamber, I propose to connect the chamber directly with the fire-box and smoke-chamber so that the hot products of combustion by passing through the chamber superheat the steam within the 40 steam-pipes.

Referring now to the drawings, Figure 1 is a vertical central section of a locomotive boiler having my improved superheater applied thereto; Fig. 2 is a section on the line 45 $y-y$, Fig. 1; Fig. 3 is a section on the line $a-a$, Fig. 2, the flues being omitted; Fig. 4 is a vertical central section of a different type of locomotive from that shown in Fig. 2 having one form of my improved superheater applied thereto; Fig. 5 is a section on the line $b-b$, Fig. 4; Fig. 6 shows a modification of

the arrangement shown in Fig. 4; Fig. 7 is a section of a modified form of boiler on substantially a line corresponding to the line $c-c$, Fig. 4; Fig. 8 is a vertical central view 60 of a boiler having another form of superheater embodying my invention applied thereto; Fig. 9 shows a modification; Fig. 10 is a section on the line $d-d$; Fig. 8; Fig. 11 is a vertical section of a locomotive boiler 65 having still another form of superheater embodying my invention applied thereto; Fig. 12 is a section on the line $e-e$, Fig. 11.

In all the forms of the invention herein shown I have arranged within the boiler shell a superheating chamber which extends longitudinally thereof, and within which chamber the steam is superheated by products of combustion which are passed through the chamber.

Referring first to Fig. 1 where my improved superheater is shown as used in connection with an ordinary locomotive boiler, 3 designates the shell of the boiler, 4 the combustion chamber, 5 the usual crown-sheet 80 forming the top of the combustion-chamber, 6 the smoke-chamber and 7 the flues which extend through the water in the shell 3 and conduct the products of combustion from the fire-box to the smoke-chamber. These parts 85 may be of any suitable or usual construction. In applying my improved superheater to this type of boiler, I place within the shell 3 a drum 8 which extends from the front flue-sheet 9 back to or nearly to the fire-box 4, 90 and which forms a superheating chamber within which the steam is superheated. The constructional details of this drum or superheating chamber and the manner of arranging it within the boiler may be varied according to the type of boiler to which my superheater is applied. As shown in Fig. 1 said drum 8 has within it a smaller drum 10, 95 which is spaced therefrom and which is secured thereto at its ends, as at 12.

The front end of the drum 8 is connected directly to the front flue sheet 9, and the rear end is connected to the rear wall 13 of a dome 14 supported on the crown-sheet 5 and communicating with the combustion chamber 4 of the fire-box. Extending through the smaller drum 10 are a plurality of flues 15 which open at one end into the dome 14 and at the other end into the smoke-chamber 6. The drum 8 is provided with an inlet 110 opening 17 which extends partially into the usual steam dome 18 so that steam from the

dome can enter the inlet and pass into the space between the drums 8 and 10. The inner drum 10 is provided at its front end and on its underside with an opening 19, and its front end is divided into two compartments by the horizontal partition 20.

21 designates a steam-pipe extending into the inner drum and nearly to the rear end thereof, said pipe passing through the front flue sheet 9 into the smoke-chamber and being connected to any suitable or usual throttle-valve 22. The stem 23 of the throttle-valve is shown as extended through said steam-pipe 21 and through the dome 14 to the fire-box end of the boiler where it is connected to any suitable throttle-lever.

The partition 20 has the centrally located extension 24, see Fig. 3, which extends nearly to the right hand end of the drum 8.

20 When the boiler is in operation part of the products of combustion pass into the dome 14 and from the dome through the flues 15 to the smoke-chamber 6, it being understood that the main portion of the hot gases pass 25 to the smoke-chamber through the usual flues 7. As the steam is formed it passes to the steam-dome 18, and passes from there into the space between the two drums, from which space it passes through the opening 19 30 into the inner drum, and because of the arrangement of the partition 20 therein said steam passes backwardly or to the right beneath said partition, and then up around the sides of the extension 24 to the upper 35 compartment of said inner drum, from which upper compartment it passes into the steam-pipe 21 and thence to the throttle-valve. During the backward movement of the steam through the lower compartment 40 of the inner drum and during its movement up around the extension 24 it is in engagement with the flues 15 through which hot products of combustion are passing and thus becomes superheated.

45 In Fig. 4, I have illustrated one form of my improved superheater as applied to a boiler such as shown in my co-pending application, Se. No. 216,315, filed July 13, 1904. This type of boiler comprises a shell 50 3^a which is to be kept filled with water, and steam-generating spaces 26 around the sides and top of the fire-box 4^a, said steam-generating spaces being connected to a steam-drum 27 in some suitable way, as by means 55 of nipples 28, and also being connected to the interior of the shell 3^a so that the water from the shell 3^a is forced into the steam-generating spaces where it is converted into steam, and the steam then passes into the 60 steam-drum 27. In this embodiment of my invention there is located within the shell 3^a a drum 8^a which forms the superheating chamber, said drum extending from the front flue sheet 9^a back to the fire-box, preferably 65 to the rear flue sheet 280. Extending

through this drum 8^a are a plurality of flues 15^a which open at one end into the combustion chamber and at the other end into the smoke chamber 6^a, so that a part of the products of combustion pass therethrough, the 70 major portion of the products of combustion, however, passing through the usual flue 7^a.

The steam-drum 27 is divided into compartments 29 and 30 by a suitable partition 31, and the compartment 29 in which the 75 steam first collects as it is generated in the steam-generating spaces 26, is connected to the superheating chamber in some suitable way, as by means of a nipple 32. Within the superheating chamber is a partition or baffle-plate 33 dividing said chamber into compartments 34 and 35, and extending forward from said partition 33 is a pipe 36 through which the steam passes from the compartment 34 to the compartment 35. Said pipe 80 extends nearly to the forward end of the compartment 35 and may be provided with lateral openings 37, if desired. The compartment 35 of the superheating chamber communicates with the compartment 30 of 90 the steam-drum in some suitable way, as through a nipple 38. Within said compartment 30 is any suitable or usual throttle-valve 22^a from which extends a steam-pipe 39 leading through the superheating chamber, and extending to the cylinders of the engine. In this form of the invention, it will be seen that the steam which is generated in the steam-generating spaces 26 passes to the compartment 29 of the steam-drum, from 100 which it passes into the compartment 34 of the superheating chamber. While within said compartment, said steam is partially dried by the heat radiating from the front end of the flues 15^a, and said steam then 105 passes through the steam-pipe 36 to the forward end of the compartment 35 of the superheating chamber, and thence passes backwardly through said compartment to the compartment 30 of the steam-drum. 110 During its backward movement within the compartment 35, it is brought in contact again with the flues 15^a, and is still further dried and superheated. In this form of the invention, as well as in the one shown in Fig. 115 1, it has been my aim to cause the steam to travel the full length of the flues, while said steam is in the superheating chamber, thereby to get the greatest possible superheating effect.

120 In Fig. 6, I have shown a slight modification of the invention shown in Fig. 4. In the latter figure, it will be noted that the superheating chamber extends clear to the flue-sheet 280. In order to prevent any danger 125 of the flue-sheet becoming overheated at this point, I may interpose a water-space between said flue-sheet 280 and the adjacent end of the superheating chamber, as shown in Fig. 6, wherein the end of the superheat- 130

ing chamber is spaced from the flue-sheet 280^a as at 40, so as to prevent said end of the superheating chamber or the flue-sheet from being burned out.

In Fig. 8, I have shown still another embodiment of my invention wherein the superheating chamber extends only part way through the shell of the boiler. In said invention, 3^b is the boiler-shell having the ordinary flues 7^b passing therethrough. 6^b is a smoke-chamber, 9^b the front flue-sheet, 280^b the rear flue sheet, 4^b the fire-box, and 26^b the steam-generating spaces around the fire-box. The type of boiler herein illustrated is 10 similar to that shown in Fig. 4, that is, the water within the shell 3^b is forced into the steam-generating spaces 26^b where it is generated into steam, and the steam passes into the compartment 29^b of the steam-drum 20 27^b through suitable nipples 28^b.

The superheating chamber is formed within a drum 8^b which extends from the flue-sheet 280^b forward part way to the front flue-sheet 9^b. Extending through this superheating chamber are a plurality of flues 15^b through which products of combustion pass from the fire-box to the smoke-chamber. The steam-drum 27^b is divided by the partition 31^b into the compartments 29^b and 30^b, 30 and the superheating chamber is also divided by a partition 33^b into two compartments 34^b and 35^b. The compartment 34^b communicates with the compartment 29^b of the steam-drum through a suitable nipple or 35 nipples 32^b, and the compartment 35^b of the superheating chamber has communication with the compartment 30^b of the steam-drum through a suitable nipple or nipples 38^b. The partition 33^b in the superheating 40 chamber has an opening 41 therein, as seen best in Fig. 10, so that the steam which collects in the compartment 29^b of the steam-drum passes through the nipple 32^b into the compartment 34^b of the superheating chamber, and thence passes through the opening 41 into the compartment 35^b, from which it passes to the compartment 30^b of the steam-drum. During its passage through the compartments of the superheating chamber, the steam is brought into contact with the flues 15^b, and thereby becomes superheated.

22^b designates any usual or suitable throttle-valve which admits the steam to the 55 steam-pipe 39^b from which pipe steam is conducted to the cylinders of the engine. The steam-pipe 39^b is protected from the cooling effect of the water within the chamber 3^b by a protector-pipe 42 which extends between 60 the superheating chamber and the front flue-sheet 9^b and surrounds that portion of the steam-pipe outside of the superheating chamber.

In Fig. 9, I have illustrated a slightly different form of the invention wherein the

superheating chamber is spaced from the front flue-sheet, and the throttle-valve is located within the smoke-chamber instead of within the steam-drum. In said figure, 70 280^c designates the flue-sheet adjacent the fire-box 4^c, 7^c are the usual flues extending through the shell 3^c and extending from the flue-sheet 280^c to the front flue-sheet 9^c, and 27^c is the steam-drum into which the steam passes from the steam-generating spaces 26^c. 75 The steam-generating chamber is formed by a drum 8^c within the shell of the boiler, and passing through said superheating chamber are a plurality of flues 15^c through which hot products of combustion pass to the smoke-chamber. The superheating chamber 80 is spaced from the flue-sheet 280^c, as at 40^c, so that the water which occupies said space will prevent the extreme heat in the combustion chamber from burning out the 85 end of the superheating chamber or the flue-sheet. The throttle-valve 22^c is, in this form of the invention, located within the smoke-chamber 6^c, and steam is taken directly from the superheating chamber. In 90 this form of the invention the steam is superheated within the superheating chamber before it is delivered to the throttle-valve by being brought into contact with the flues 15^c.

In Figs. 11 and 12, I have illustrated still 95 another way in which my invention may be embodied. In the boiler herein illustrated, 3^d is the shell of the boiler having the smoke-chamber 6^d at one end of the boiler and the fire-box 4^d at the other, and 7^d are the usual flues connecting the smoke-chamber and fire-box. Surrounding the fire-box are steam-generating spaces 26^d which communicate with the compartment 29^d of the steam-drum 27^d, so that the steam which is generated 100 within said steam-generating spaces is delivered to said compartment 29^d. Within the shell 3^d is a drum 8^d constituting the superheating chamber, and extending through said drum from the flue-sheet 280^d to the 105 front flue-sheet 9^d are a plurality of flues 15^d through which hot products of combustion pass. The steam-drum 27^d is divided into the two compartments 29^d and 30^d by the partition 31^d, as in the forms of the invention last described. In the form of the invention herein illustrated, however, I place within the fire-box of the locomotive extra superheating pipes 46 which open at one end 110 into the superheating chamber, and at the other end into a steam-chamber 47 which has communication with the compartment 29^d of the steam-drum. The superheating chamber communicates with the compartment 30^d of the steam-drum through any 115 suitable means, such as nipples 38^d, and within said compartment 30^d is the throttle-valve 22^d which controls the admission of steam to the steam-pipe 39^d extending through the superheating chamber into the 120 130

smoke-chamber 6^d. In this form of the invention the steam which is generated in the steam-generating spaces of the boiler accumulates in the compartment 29^d of the steam drum, passes from thence into the space 47, and thence through the superheating-pipes 46 into the superheating chamber. From the superheating chamber the steam passes into the compartment 30^d of the steam-drum, 10 from which it is taken to the engine-cylinders. Herein the steam is partially superheated in the pipes 46 by the direct action of the hot gases in the combustion chamber, and is further superheated within the superheating 15 chamber by the action of the flues 15^d.

In Fig. 12, which is a section on the line *e*—*e*, the nipples 47, forming a communication between the interior of the shell 3^d and the steam-generating spaces 26^d, are shown. 20 In the forms of the invention thus far described, the steam is admitted directly to the superheating chamber and is superheated therein by hot gases in flues extending through said chamber.

In Fig. 7, I have illustrated another arrangement of superheating chamber. In said figure, which is a cross section through a boiler on a line corresponding to the line *c*—*c*, Fig. 4, 3^h designates the shell of the boiler, and 27^h the steam-drum. The superheating chamber is the space 60 above a horizontal partition 8^h extending across the upper end of the shell 3^h, the space below said partition being filled with water and the 35 space above being filled with steam. Said superheating chamber 60 communicates with steam-generating spaces around the fire-box in some suitable way, and extending through said superheating chamber are a plurality of 40 flues 15^h, said flues opening at one end into the combustion chamber, and at the other end into the smoke-chamber. As the steam is admitted to the superheating chamber, it passes through a pipe 36^h which is similar to 45 the pipe 36 in Fig. 4, and is thus distributed throughout the superheating chamber and comes into contact with superheating flues 15^h.

In most of the forms of my invention 50 wherein a steam-drum is used, I prefer to provide within the drum a baffle-plate 61 which is situated between the point where the steam is admitted to the drum from the steam-generating spaces, and the point where 55 the steam is delivered from the drum to the superheating chamber, said baffle-plate operating to prevent any water in the steam from being carried over into the superheating chamber.

In Fig. 1, I have illustrated a sleeve or 60 pipe 62 as extending through the dome 14, through which pipe or sleeve the throttle-valve stem 23 passes. This sleeve 62 can be expanded into the sides of the dome to make 65 a tight joint, and thus prevent any leakage

around the valve-stem. In this form of the invention, the valve-stem would be packed, as at 64, where it emerges from the shell. 66 designates a valve which may be placed in the partition in the steam-drum, and by 70 means of which more or less saturated steam from the compartments 29, 29^h, 29^d, etc. may be delivered to the other compartment of the steam-drum in case it should happen that the steam was superheated beyond the 75 desired point in passing through the superheating chamber. By conducting more or less saturated steam directly through the partition in the steam-drum the temperature of the steam used in the cylinders may be 80 regulated as desired. This valve 66 may be operated by any suitable valve-stem extended to the cab of the engine.

In all the above-described forms of my invention, I employ a superheating chamber 85 within the shell of the boiler through which chamber the steam is taken and within which chamber said steam is heated by the action of hot gases which are also passed through the chamber.

Although I have illustrated my invention as applied to locomotive boilers of different types, it will be observed that the invention is not limited to its use with locomotive boilers, but may be applied to any steam-boiler.

Having fully described my invention, what I claim as new and desire to secure by Letters Patent is:—

1. In a locomotive boiler, a shell having a smoke-chamber at one end and a fire-box at the other, a superheating chamber located entirely within the shell, means to admit the steam into the superheating chamber, means to superheat the steam while in the chamber, and a pipe, a portion of which is located within the shell, to convey the superheated steam from said chamber to the engine cylinder, said pipe being separate from the means to superheat the steam and from the superheating chamber, the portion of the pipe that is located within the shell being protected from contact with the water.

2. In a locomotive boiler, a shell having a smoke-chamber at one end and a fire-box at the other, a horizontal superheating chamber within said shell above the normal water level therein, and flues extending longitudinally of the shell and all opening at one end into the fire-box and at the other end into the smoke-chamber, a portion of said flues passing through the superheating chamber.

3. In a locomotive boiler, a shell having a smoke-chamber at one end and a fire-box at the other, a horizontal superheating chamber within said shell above the normal water level therein, flues extending longitudinally of the shell and all opening at one end into the fire-box and at the other end into the smoke-chamber, a portion of said flues pass-

- ing through the superheating chamber, and a pipe to convey superheated steam from said superheating chamber to the engine cylinders, said pipe being protected from contact with the water in the steam and water chamber. 5
4. In a locomotive boiler, a shell, a smoke-chamber at one end of the shell, a fire-box at the other end thereof, a superheating chamber within the shell, a longitudinally extending drum exterior to the shell and communicating both with the steam and water spaces of the boiler and with said superheating chamber, and means within the superheating chamber to superheat steam. 10
5. In a locomotive boiler, a shell, a smoke-chamber at one end of the shell, a fire-box at the other end, a superheating-chamber within the shell, a drum exterior to the shell and communicating with the steam and water spaces of the boiler, said drum also communicating with the superheating chamber, and flues extending through the shell and communicating at one end with the fire-box and at the other end with the
- smoke chamber, a portion of said flues passing through the superheating chamber. 25
6. In a locomotive boiler, a shell having a fire-box at one end and a smoke-chamber at the other end, a superheating chamber within the shell, a drum exterior to the shell, a partition extending across the drum and dividing it into two compartments, one of which communicates both with the superheating chamber and the steam spaces of the boiler, and the other of which communicates with the superheating-chamber, and flues communicating at one end with the fire-box and at the other with the smoke-chamber, a portion of said flues extending through the superheating chamber. 30 35 40

In testimony whereof, I have signed my name to this specification, in the presence of two subscribing witnesses.

JAMES M. McCLELLON.
